UNITED STATES PATENT OFFICE.

WILLIAM E. WORTH, OF SAN FRANCISCO, CALIFORNIA.

LETTERING-PEN.

1,136,196.

Specification of Letters Patent. Patented Apr. 20, 1915.

Application filed March 11, 1914. Serial No. 523,684.

To all whom it may concern:

Be it known that I, WILLIAM E. WORTH, a citizen of the United States, residing in the city of San Francisco, county of San Francisco, and State of California, have invented certain new and useful Improvements in Lettering-Pens, of which the following is a specification.

My invention relates to lettering pens and has for its principal object to provide in a lettering pen a pen stock and holder having in connection therewith an open ink reservoir or pocket and adapted to receive, detachably and interchangeably, lettering pen points of different sizes, and to hold them in communication with the ink reservoir or pocket, thus making it possible to use pen points of various sizes with the same holder and ink reservoir, and also to quickly and easily detach the pen point for purposes of cleaning it and the ink reservoir, thus greatly facilitating this cleaning operation which is an objectionable feature with lettering pens now in use.

Lettering pens are now made in various sizes, and are sold in sets, each pen, however, being complete in itself, including stock or handle. The pen points are not detachable from the ink reservoir or cup, and are, therefore, very difficult to clean. By means of my improvement, one holder only, with its ink reservoir, is required, and only the pen points are made in sets of varying sizes and all fitted to the same holding device and ink reservoir.

In order that others may fully understand my invention, I have shown one practical embodiment thereof in the accompanying sheet of drawings, which I will now describe.

Figure 1 is a side elevation of a lettering pen embodying my invention; Fig. 2 is a top plan view thereof, with a portion of the stock broken away; Fig. 3 is a bottom plan view thereof with a portion of the stock broken away; Fig. 4 is a cross sectional view taken on line 4-4 of Fig. 1; Fig. 5 is a bottom plan view of a pen having a smaller point; Fig. 6 is an edge or side view thereof.

In the embodiment of the invention here shown for purposes of illustration, 1 designates the stock or handle, 2 a pen holding device with ink reservoir therein, and 3 a lettering pen, said lettering pen being detachably secured to the holding device 2 by

means of a little thumb screw 4. The pen holder proper, as here shown, comprises the stock or handle 1 and the holding device 2, made separate and secured together, the holding device having formed therein an open spoon-like ink reservoir 2^a, into which the ink is placed in the same manner that it is put into a ruling pen. The outer end of the holding device, this being the delivery end of the ink reservoir, is adapted to form a seat for the lettering pen 3, in this form the end being cut out V-shape, as indicated at 2^b, Fig. 3, and the pen is adapted to fit snugly therein, substantially in the manner shown.

The pens 3, as here shown, have flat bodies made tapering at one end and terminate in a writing point, bent to an angle, preferably, as at 3^a. These pens may be of any desired size and form, at their writing ends, while the bodies are standardized and all adapted to one holding device and reservoir. The pen points are split through their ends, as indicated, and are formed at the angle to be seated in the end of the holding device. The body of the pens 3 are slotted at their rear ends, as at 3^b, whereby to be inserted under the head of the thumb nut 4, as indicated. Thus it is only necessary to slightly loosen said thumb nut 4 and withdraw the pen from the holder, making it very easy to change one pen for another, and to clean both the pen and the ink reservoir or cup 2^a.

I am aware that slight changes can be made in the invention as here illustrated without departing from the spirit thereof, and I do not, therefore, limit the invention to the showing made, except as I may be limited by the hereto appended claims.

What I claim is—

1. In a lettering pen, a pen holding body having a spoon-like ink reservoir formed therein with its extreme end shaped to seat a pen theracross at an angle thereto, and a pen having a body detachably secured to said holding body and having its end formed into a round, split writing portion bent to an angle with its body and seated across said reservoir at an angle thereto and extending beyond the reservoir, substantially as described.

2. In a lettering pen, in combination, a pen holding member provided with an ink reservoir, and a lettering pen having a round, split writing end and detachably

mounted across said pen holding member at an angle thereto with its split portion positioned to receive ink from said reservoir.

3. A lettering pen of the character described comprising a stock or handle, a pen holding device having formed therein a spoon-like reservoir with its discharge end cut out to form a seat for a lettering pen, and a lettering pen having a body portion 10 overlying said reservoir with means for detachably securing it to said holding device and provided with a rounded writing end seated across and projecting beyond the discharge end of said reservoir, substantially 15 as described.

4. In a lettering pen, in combination with the stock or handle, a combination pen holding device and ink reservoir, and a pen having a rounded, split writing end detachably mounted thereon with its writing end bent 20 to an angle and seated in intersecting relationship with the discharge end of said ink reservoir, substantially as described.

Signed at Portland, Multnomah county, Oregon, this 28th day of February, 1914.

WILLIAM E. WORTH.

In presence of—

G. M. BARTHOLD,
ALFRED P. DOBSON.
